SHINGLE ROOF

Ernest Bussey, Birmingham, Ala.

Application July 17, 1933, Serial No. 680,817

4 Claims. (Cl. 108—7)

My invention relates to improvements in roofing shingles and the method of forming same, and has for an object the provision of a diamond type composition shingle which can be cut from a standard roll of roofing material without wasting any of the material, and which can be laid and secured in position on a roof in less time than is required when laying other types of shingles.

10 My invention further contemplates the provision of improved means by which the shingles can be accurately positioned with respect to each other in order that the several rows of shingles will be parallel to the eaves of a roof, and the 15 area of the exposed surface or showing of the shingles will be uniform throughout.

My invention further contemplates the provision of improved means for fastening the shingles in position on a roof whereby they are secured 20 against displacement due to exposure to the sun, wind and rain.

My invention has other features which will be hereinafter set forth in the specification, and shown in the accompanying drawings, wherein

25 Fig. 1 is a plan view of a piece of strip or roll roofing material and shows the lines along which the material is cut to form the shingles;

Fig. 2 is a plan view of one of my improved shingles;

30 Fig. 3 is a plan view illustrating the manner in which the shingles are laid parallel to the eave of a roof, and the means employed to secure them against displacement;

Fig. 4 is a plan view showing a plurality of shingles laid adjacent a roof valley, and demonstrates the value of my improved aligning means;

Fig. 5 is a sectional view taken along the line V—V of Fig. 3;

Fig. 6 is a plan view showing a piece of roofing 40 material and cutting lines for forming a modified form of my invention;

Fig. 7 is a plan view of the modified form of shingle; and

Fig. 8 is a plan view which illustrates the manner of laying my modified form of shingle shown in Fig. 7.

Referring to Fig. 1 of the drawings, my improved shingle is manufactured preferably by taking a standard strip of roofing wide enough to form two rows of shingles and slitting it centrally, forming two strips each having opposed parallel straight edges 2 and 3. The strips are cut transversely along zigzag lines at distances equal to the distance between the lines 2 and 3 to form individual shingles. The transverse cuts are along

lines 4 extending at an angle of 45° to the edge 3 for a short distance, then along lines 8 extending perpendicular to the edge 3 the major portion of the distance across the strip and then along lines 5 inclined at 45° to the line 8 and the edge 2, to the point of intersection with the edge 2, the lines 4 and 5 being equal in length and oppositely inclined with respect to the line 8. 5

Each of the shingles thus formed has two opposed corners cut away and the other two opposed corners with projections or ears equal in area to the cut away portions and with a short edge equalling in length the boundary lines or edges of the cut away portions. This feature is important in providing a ready means for laying and aligning the shingles as will be more particularly described hereinafter.

In Fig. 2 of the drawings, I show an individual shingle formed as just described turned to the position it occupies when laid on a roof. As 20 shown, it comprises a body portion 11, with triangular ears 12 and 13 on the opposed horizontal corners of the shingle, formed by the diagonal cuts 4 and 5, said ears being oppositely inclined and on opposite sides of an imaginary horizontal center line across the shingle. The ear 12 has an upper horizontal edge 14 and the ear 13 has a lower horizontal edge 16.

The upper portion 17 of the shingle has a horizontal edge 19 and the lower portion 18 has a horizontal edge 21, the edges 19 and 21 being equal in length and parallel to the horizontal edges 14 and 16 of the ears 12 and 13. In order to aid in aligning the shingles as they are being laid on a roof, I provide markings 22 and 23, which are 30 vertically opposite the centers of the lines 14 and 16 so as to form right angle triangles with adjacent edges of the ears 12 and 13.

The shingles are laid as shown in Figs. 3 and 5, wherein a roofing strip 24 is first secured in position along the eave of the roof 26 by means of 40 nails (not shown). The first row of shingles is then laid upon the strip, preferably working from the left side of the roof to the right side, and secured against displacement by means of nails 45 27 driven through ears 12 and 13 and by roofing cement 28 interposed between the strip and the lower portion 18 of each shingle. In laying the first row the lower horizontal edge 21 of each shingle is made to coincide with the lower horizontal edge of the strip 24, and the horizontal edge 14 should be made to coincide with the upper horizontal edge of the strip 24. The marks 22 and 23 on adjacent shingles are placed opposite each other and the ears 13 are positioned below the 50 55

ears 12 of adjacent shingles. This insures an accurate laying of the shingles with unskilled labor.

The width of the strip 24, it will be seen, should be equal to the vertical distance from the horizontal edge 21 to the horizontal edge 14 in order

- 5 that the top and bottom edges of the strip may be used in aligning the first row of shingles. When the first row of shingles have been laid as above described, it will be noted that the ears 12 and 13 10 abut to form a web 29 between the shingle bodies 11, which is defined by the horizontal edges 14 and 16.

In laying the second row of shingles, their horizontal edges 14 and 21 are positioned in alignment 15 with the edges 19 and 16, respectively, on the first row of shingles and with the aligning marks 22 and 23 opposite each other. Also the upper right hand diagonal edge of the top shingle intersects the angle formed by the meeting edges at 20 the upper end of the underlying shingle. This gives three distinct checking points to insure accuracy in laying the shingles. The ears 12 and 13 of the second row of shingles are then nailed to the roof and their lower portions 18 are secured 25 to the web 29 formed by the underlying ears 12 and 13 by means of roofing cement 28. The roofing cement serves as a plastic bond to hold the lower portions 18 of all shingles in position and also protects the nail heads which are completely 30 covered by the cement.

The shingles may be laid with equal facility beginning at the right and working toward the left. In such a case, the second row is laid by placing the mark 23 on the shingle being laid in 35 register with the mark 22 on the next shingle to the right, placing the edge 21 on the shingle being laid to coincide with the lower edge of the web 29, and placing the edge 14 to coincide with the edge 19 on the underlying shingle. The shingle 40 is then fastened down as before described.

It will be seen that, working in either direction, there are three aligning locations on the shingles, remote from each other, which insures extreme accuracy in laying.

45 The aligning marks 22 and 23 are especially useful to assist the workmen in maintaining a uniform lap for the shingles on the roof and in laying the shingles adjacent a valley in a roof, as illustrated in Fig. 4. By placing the marks 22 50 provided on the shingle fragments 31 in alignment with the marks 23 on the adjacent shingles, they will be correctly positioned. The marks thus take the place of the aligning edges which will not be available.

55 In Figs. 6, 7 and 8 I show a modified form of shingle 35 provided with a generally square body portion 36 and one ear 37 which is similar to the ear 13 provided on the preferred form of shingle. The ear 37 is provided with a horizontal aligning 60 edge 37a corresponding to the edge 16 shown in Fig. 2, and which is parallel to an aligning edge 38 formed at the lower corner 39 corresponding to the edge 21 shown in Fig. 2. Aligning marks 40 and 41 are provided on the corner adjacent the 65 ear and on the corner 43. This form of shingle is cut from a strip 44 by slitting it centrally along the line 46 and transversely along the straight lines 47 and zigzag lines 48, similar in direction and length to the lines 4, 5 and 8 shown in Fig. 1, 70 the lines 47 and the portion of the lines 48 perpendicular to the edges being spaced apart a distance equal to the transverse width of the shingle so as to produce a generally square shingle.

In laying the shingles 35, those in the lower 75 row are positioned and secured on the strip of

roofing material 49 by means of nails 27 and roofing cement 28, one nail being driven through the ear 37, and the other nail being driven through the opposed corner 43 of the shingle.

The shingles in the second row are aligned by placing their lower aligning edges 38 over the aligning edges 37a on the underlying shingles, and by positioning the aligning marks 41 in alignment with the edges 51 of the underlying shingles. The aligning marks 40 are particularly 10 useful in laying shingles along the valley of a roof, as shown in Fig. 4, as the side edges 52 of the underlying shingles can be placed in alignment therewith to provide the correct overlap.

The shingles in the upper rows are secured by 15 nailing as above set forth, and by means of cement 28 placed on the upper corner 50 on the underlying shingles to hold the overlying corners 39 against displacement. A thin coating of cement is also placed on the ears 37 and the corners 20 43 to protect the nail heads and to prevent the corners 39 from curling upwardly.

From the foregoing, it will be apparent that I have provided a shingle affording a maximum of roof coverage per shingle, with a minimum 25 but adequate marginal overlap, and which may be laid with a minimum of nailing, only two nails to a shingle being employed. The longer lower edges lie flat on the underlying shingles with the lower end of the shingle when laid held down by 30 roofing cement only which covers and protects the nails in the underlying shingles. This cement forms a plastic and somewhat elastic bond that takes the place of any clip or mechanical hold-

down and not only leaves the shingle tip imperforate, but, what is more important, it leaves the side joints of the butt free of any interposed element that will hold them open or in any way space the joint members or break the continuity 35 of surface contact between the side edges of the 40 butts and the underlying shingles or roof elements. The side joint elements of composition shingles, when thus held against displacement, will, in due course, and in the manner normally 45 to be expected as a result of the action of the 50 elements, become integrally united. The cement is shown as occupying a roughly circular area which is the natural shape a dab will take when spread between the opposed shingle surfaces to its service position. In such position it becomes 55 merely a film of adhesive which acts to bond but which will not constitute an interposed element that will space the joint members that it bonds.

It will be noted that this joint area lies inwardly 60 from the outer edges of the side joints. This 65 position is important because with side joints unsealed, the cement should not be placed as to trap or divert inwardly any water that might 70 work its way into the joint. With the joint members properly laid and securely held in surface contact, water cannot find its way far enough into the joint to be trapped by the cement bond. Moreover, the prescribed method of applying the cement in a concealed dab keeps it back from the 75 exposed edges of the corner joints and preserves the unmarred attractive appearance of the roof. Further, the cement applied as a dab over match marks 22, 23 at the foundation center, requires no careful work on the part of the 80 cementer and consumes a minimum amount of cement per square of roof. The angle which the lower diagonal edges of the shingle present to the roof prevents water from running under the edges of the shingles and the roof thus covered 85 is free from leakage.

These advantages, coupled 90

with the fact that the shingles may be accurately and rapidly laid by unskilled labor, provide a shingle which is extremely economical of use as well as attractive in appearance.

5 While I have shown my invention in but two forms, it will be obvious to those skilled in the art that it is not so limited, but is susceptible of various other changes and modifications, without departing from the spirit thereof, and I desire, 10 therefore, that only such limitations shall be placed thereupon as are imposed by the prior art or as are specifically set forth in the appended claims.

What I claim is:

15 1. A composition shingle roof laid with shingles having tapered spaced butts and juxtaposed side anchorage corners disposed to be overlapped by the tip of the butts of the shingles in the next upper course, nails applied through said corners to anchor the shingles, and cement applied over the nail heads and under the butts to hold the downwardly converging side edges of the butts fast in tight uninterrupted surface contact with the underlying roof elements, substantially as and 20 for the purposes described.

2. A roof covering laid with shingles having tapered butts and juxtaposed side corners overlaid by the butts, nails applied to said corners to anchor the shingles at each side, and cement applied between the butts and underlying roof elements and constituting the sole means as the shingles are laid to anchor the butts with their side edges held in close surface contact with the underlying roof elements.

5 10 3. A roof covering laid with diamond type shingles having tapered spaced butts and juxtaposed side anchorage corners adapted to form foundation for the tips of the butts of the shingles in the next upper course, nails applied to said corners to anchor the shingles, and a dab of 15 cement applied on said foundation under each of the butt tips and spaced inwardly from its side edges.

15 4. A roof covering according to claim 3, in which the anchorage corners lie level and abut 20 along a diagonal line bisecting the foundation and have matching markers at the center of each foundation.

ERNEST BUSSEY.
